AUTOMATIC VOLUME CONTROL

Harold A. Wheeler, Great Neck, N. Y., assignor to
Hazeltine Corporation

Application August 14, 1931, Serial No. 556,979

19 Claims. (Cl. 250—20)

This invention relates to amplifiers for use in the reception of modulated carrier frequency signals, wherein the amplified signal voltage is automatically maintained at a substantially predetermined level.

Various systems for providing "automatic volume control" have been developed which continuously adjust the gain of the amplifier stages of a radio broadcast receiver, so that the signals are reproduced with substantially even volume regardless of the strength of the carrier frequency input energy to the receiver. However, the present systems, which obtain automatic volume control of the received radio signals involve supplying the detector with a large amplified signal voltage. This large amplified signal voltage is necessary in order that the fluctuations in the grid biasing voltage of the tube upon which the automatic volume control acts shall be sufficiently large adequately to control the volume through a considerable range of amplification ratios. And large amplified signal voltages require the use of a considerable number of amplification stages prior to the detection stage of the receiver.

It is the object of the present invention to overcome the above noted objection to the ordinary automatic volume control receiver and to provide an automatic volume control for a radio receiver which does not require a large amplified signal voltage to be supplied to the detector in order to obtain a sufficiently large variation in the bias of the amplifiers.

A disadvantage which is common to radio receivers employing an automatic volume control, is that they are sensitive to surges or pulses, causing what is known as "motor boating."

Therefore, it is a secondary object of the present invention to provide a balancing circuit which is adjusted in both amplitude and phase to cancel the modulation effects due to undesired fluctuations in the source of direct voltage for the anodes of the tubes which receive the automatic volume control bias, which fluctuations produce the "motor boating" effect.

In accomplishing the objects of the present invention, a sensitive grid-leak detector and an added D. C. amplifier tube are used. The latter tube, which is hereinafter called the "volume control tube," performs three functions: It amplifies or repeats the changes of potential occurring in the detector plate circuit; it reverses the direction of the changes; and it supplies the resulting changes as an automatic control grid bias to one or more of the tubes preceding the detector. These functions are accomplished with a common

source of direct current, as will be described more fully hereinafter. The initial value of the grid bias on the tubes preceding the detector is adjusted by varying the operating potentials of the automatic volume control tube, as will be described hereinafter.

The object of the invention relative to the prevention of "motor boating" is accomplished by varying the bias of one or more radio frequency amplifier tubes by an amount sufficient to compensate for the variation in plate potential, the variation in bias being 180° out of phase with the variation in plate potential.

Attention is now invited to the drawing in which the single figure shows a circuit diagram of a signal responsive system in the form of a radio receiver incorporating a fluctuation compensating network according to the present invention.

The carrier frequency current is impressed upon the radio frequency amplifier 12 by the antenna circuit, which includes the antenna 10 and the ground 11. As indicated in the drawing, the carrier frequency amplifier comprises four tuned radio frequency coupling systems 13, which are tuned simultaneously by means of condensers and a uni-control mechanism which are not shown. These coupling systems include three radio frequency amplifier tubes 14. The gain of amplifier 12 is controlled by the bias voltage on the grid, or control electrode, of one or more of the tubes 14. This is accomplished by means which will be described hereinafter.

The radio frequency amplifier 12 may be replaced by a superheterodyne arrangement or any other amplifying arrangement, the specific details of which constitute no part of the present invention.

If triode vacuum tubes are used in amplifier 12, it may be advantageous to neutralize the inherent grid plate capacity coupling by one of the well known neutralization circuit arrangements. Screen grid tubes may also be used, in which case neutralizing means will be unnecessary.

The output of the radio frequency amplifier 12 is connected to a detector, or rectifier, circuit which circuit produces a uni-directional voltage dependent on the impressed alternating current signal strength. The circuit utilizes the familiar type of detection which is commonly referred to as grid current rectification. The detector circuit includes the three electrode detector tube 21, having the grid condenser 24 and grid-leak 25 in its grid circuit. The plate circuit of the detector 21 includes the condenser 26 for bypassing radio

frequency currents between the plate and cathode, and the primary coil of the audio frequency transformer 29, for coupling the audio frequency output of the detector to the audio frequency 5 amplifier.

The output of the transformer 29 is applied directly to the high resistance potentiometer or voltage divider 30. By this means any desired portion of the total secondary voltage of transformer 29 may be applied to the grid of the audio frequency amplifier tube 22. The amplifier 22 is in turn coupled through the audio frequency transformer 33 to the grids of a push-pull amplifier comprising the two tubes 23. The output 10 of the tubes 23 is coupled through audio transformer 36 to the voice coil of loud speaker 37. The circuits so far described operate in the manner well known in the art and need no further description.

20 The grid and the plate, or anode, potentials for the various tubes of the receiver are supplied preferably by a unitary source of direct voltage from filtered rectified alternating current. The positive output terminal of the alternating current power supply rectifier (not shown) is connected to terminal 58 and the negative terminal is connected to terminal 59. The ripple filtering system comprises the three high capacity condensers 57 and the choke coils 55 and 56 connected as 25 shown. One of these coils, as for example 55, may also serve as the field magnetizing coil of the speaker 37, if such a magnetizing coil is required in the speaker to be used. The required direct voltages for operating the receiver are obtained by 30 use of a group of resistances 50, 51, 52, 53 and 54, which are connected in series between the positive and negative terminals 58 and 59 of the 35 rectifier and filter system.

40 The radio frequency amplifier plate, or anode, voltages are supplied through lead 65 which is connected to the point between resistances 51 and 52. The meter 20 is connected in this lead and, therefore, measures the total radio frequency 45 amplifier plate current. The action of meter 20 is described in copending application of Harold A. Wheeler, Serial No. 302,879 filed July 7, 1927. Two by-pass condensers 17, which are effectively 50 in parallel with resistor 52, prevent radio frequency coupling between the various stages of 55 the amplifier. Resistor 18 assists in this function without materially impeding the flow of direct current. The cathodes of the amplifier tubes are connected to ground, which is the junction point between resistors 52 and 53.

55 The detector plate potential is supplied through the lead 66, connected to the terminal 58. Included in this lead is the resistance 28 which cooperates with the audio frequency by-pass condenser 27, to reduce the flow of any residual ripple current in the plate circuit of the detector tube 21. The plate current of the audio frequency amplifier tube 22 is also supplied by the lead 66 from the terminal 58. This latter connection is made through a resistance 32. An 60 audio frequency by-pass condenser 31 is provided as shown connected between the cathode of amplifier tube 22 and the end of the primary coil of the output transformer which is remote from the anode of the same tube. The grid bias potential for the amplifier 22 is supplied by the lead 63, connected to the junction of resistances 65 58 and 54.

70 The plate voltage of the push-pull amplifier stage including the tubes 23, is supplied directly from the connection 68 to the high potential end

5 of the filter. The grid bias voltage of this stage is obtained from connection 60 and is rendered free of ripple by means of series high resistance 35 and the by-pass condenser 34. The cathodes of this stage are not grounded, but are kept at the correct potential by means of lead 61, which is connected as shown between the chokes 55 and 56.

The detector circuit, including tube 21, is designed to give substantially linear relationship 10 between percentage modulation and audio frequency output, providing the carrier input voltage applied to the grid condenser 24 is in the neighborhood of from one-half to two volts. This is accomplished by the use of a high resistance grid-leak 25 which permits a negative rectified voltage on the grid nearly equal to the peak 15 value of the applied radio frequency voltage. Overloading, due to excessive reduction of the plate current by the rectified negative grid voltage, is reduced to a minimum by supplying the 20 plate current from high voltage lead 66 through the high resistance 28. The result is that an increased value of negative voltage on this grid is largely compensated for by the increasing positive voltage on the plate. It is observed that, 25 owing to the resistor 28, the voltage of the plate, or output electrode of the tube is less positive than the plate voltage supply thereof at terminal 58, but changes positively when the signal strength increases.

30 The circuit of the automatic volume control tube 42 will now be described. The volume control tube 42 is a triode including the usual cathode, grid and anode. It acts as an amplifier or repeater of changes in potential at point 41 in 35 the detector plate circuit.

Connected to the point 41 in the detector plate circuit is a lead 62 connected to the low potential 40 end of the filter voltage divider. Included in this lead are resistances 38 and 39 in series, the junction point 40 of which is connected to the grid of the tube 42. Because of the connection of resistor 38 (in a circuit across the direct voltage source) between points 40 and 41, the output electrode of the detector is maintained at a voltage which is substantially positive relative to the input, or control, electrode of the volume control tube 42. The cathode of the volume control tube is connected to a variable tap on the resistor 50, by which means the bias of the grid of the volume control tube can be accurately adjusted, so that the cathode of the volume control tube is at a potential slightly less negative or more positive than that of point 40, and the tube has a slight negative bias. In other words, the control electrode of the volume control tube is normally (i. e. in the absence of signal output from the radio frequency amplifier) maintained at a voltage slightly more negative than that of the cathode thereof. The output electrode potential 55 of the volume control tube is supplied by the lead through point 48 and the resistor 49 to ground, which, it is to be noted, is substantially positive relative to any point on the resistor 50. It follows that the cathode of tube 42 is maintained at 60 a voltage greatly negative relative to ground, and consequently, relative to the cathodes of amplifier 42. The point 48 is also connected to the control grids of the amplifier 42 through the resistor 44, thus providing a direct-current connection from the anode of the volume control tube to the said grids. Thus the point 48 and the anode of the volume control tube 42 are positive relative to both the cathode and grid of tube 42 65 but the anode of tube 42 is normally maintained 70 at a potential slightly negative relative to ground. The point 48 is also connected to the control grids of the amplifier 42 through the resistor 44, thus providing a direct-current connection from the anode of the volume control tube to the said grids. Thus the point 48 and the anode of the volume control tube 42 are positive relative to both the cathode and grid of tube 42 75 but the anode of tube 42 is normally maintained

slightly negative relative to the cathodes of amplifier 12 because of the voltage across resistance 43. The grid bias connections of the tubes 14 are returned to ground through radio frequency bypass condensers 15 and radio frequency couplings from one circuit to another are prevented by means of resistors 16, which, however, do not impede the flow of direct current.

It is observed that each of the electrodes of the control tube 42 is connected to a point of the unitary voltage source which is maintained, by an individual connection to the unitary voltage source, more negative than the most negative electrode of the detector tube.

15 The point 41 in the grid bias connection is connected to the lead 64, which is a point more negative than ground, through resistor 45 and condenser 46, the function of which will be described later.

20 The operation of the present invention will now be described.

The initial value of the potential at the point 48 which is the grid bias potential of the tubes 14 is adjusted by means of the contact on the resistor 50 which determines the negative voltage of the cathode of volume control tube 42, and therefore the grid bias of the latter tube. In the absence of any incoming signal, this contact is adjusted so that the meter 20, which indicates 25 the value of the plate current in the tubes 14, indicates the maximum permissible degree of amplification. In other words, the adjustment of the potential of lead 49 effectively varies the grid bias of the tube 42, and, therefore, varies 30 the current in the plate circuit thereof through the resistance 43. This latter, of course, varies the potential of the point 48, which thus may be 35 adjusted to the required grid bias potential.

Having performed this adjustment, a signal is 40 received by tuning the amplifier 12, and the amplified carrier frequency voltage is impressed on the detector 21. This causes a uni-directional change of voltage, namely a decrease in the detector plate current which decreases the potential difference between the point 41 and the connection 66. In other words, the potential of point 41 and of the output electrode of the detector 21 becomes more positive in the presence 45 of an amplified signal from the preceding amplifier 12. The average current of the detector output electrode changes in response to increasing the signal output of said amplifier, by an amount which is substantial as compared with the current flowing in the path comprising resistors 28, 50 33 and 39. Consequently, the voltage on the said output electrode likewise changes by an amount which is substantial as compared with the voltage difference between the detector output electrode and the control electrode of volume 55 control tube 42.

Part of this positive change occurs also at point 48, where it is applied to the grid of the volume control tube 42, with the result that the control electrode of the volume control tube becomes proportionally more positive in the presence 60 of an amplified signal. This causes an increase in the plate current of the tube 42 and thereby an increase in the negative potential of the output electrode of the volume control tube 65 and an increase in the negative grid bias potential applied to the tubes 14. In this way the gain, or amplification, of the amplifier 12 is reduced in accordance with the intensity of the incoming signal, with the result that the amplified signal applied to the detector is maintained sub-

stantially constant even though the strength of the incoming signal varies over a wide range. The action of the automatic volume control arrangement just described is, however, sufficiently slow so that the audio frequency modulation of the signal is substantially unaffected. At the same time it is sufficiently responsive to materially reduce the effect of "fading", and also to respond to changes in the intensity of the signal being received as the set is tuned from one station to another. The action of the automatic volume control, which tends to produce an audio output signal of the same mean intensity regardless of the intensity of the received signal, makes it difficult to observe by ear the correct 10 setting of the tuning control associated with the radio frequency transformers 13. For this reason, the meter 20 is associated with the radio frequency amplifier 12. The meter 20 may be observed to assist in obtaining the correct tuning 15 point. In this function the meter 20 is commonly referred to as a "tuning meter", which is now well known in the art.

Since the signal input to the detector is maintained substantially unvarying, it is necessary 25 to adjust the gain of the audio frequency amplifier in order to adjust the intensity level at the loud speaker 37. This "volume level control" function is performed by the voltage divider 30

in a well known manner.

The degree to which the tube 42 amplifies the fluctuations of potential at the point 48 may be somewhat increased by utilization of a regenerative action which is inherent in this circuit. At the same time this action must not exceed a certain maximum permissible value, because the tube 42 would then be subject to a trigger effect and the circuit, as a whole, would be inoperative. With the circuit constants, which will be given in detail below, this regenerative effect is utilized 40 to a useful but not excessive degree. The theory of this action is as follows: A positive change in the potential at point 40 causes a negative change in the potential at point 48 and a decrease in the plate current of tubes 14. This decrease in 45 the plate current is relatively large, which results in an increase in the current through resistors 51 and 52 and a decrease in the current through resistors 50, 53 and 54. In other words, there is caused thereby a positive change of all 50 potentials in the voltage supply system. This in turn produces a positive change of the potential of point 40, which aids the initial positive change which was assumed to be applied thereto.

In this receiver, when working the push-pull stage at high output levels, the resulting disturbance of the source of direct voltage having the undesired fluctuations tends to modulate the tubes 14 in the amplifier 12. This results either in a continuous oscillation of a low audio frequency above referred to as "motor boating," or in distortion of the received signal. In accordance with one of the objects of this invention, the modulation tendency is reduced to a minimum by employing a modulation balance through 65 condenser 46 and resistor 45. By this means there is superimposed upon the grid bias potential a modulating fluctuation which is equal and opposite in effect as compared with the modulating action of the fluctuations in the plate voltage of 70 the tubes 14. Of the two elements 45 and 46, the condenser 46 is the more important. The resistance 45 serves principally to correct the phase of the fluctuation superimposed on the grid bias voltage. It is observed that the ele- 75

ment 46 is connected to the connection 64. In order that the modulation balance may be effective, it is necessary that the audio frequency amplifier tubes shall not be connected to any point on the resistors 52 and 53; otherwise, this balance action might be materially disturbed. This condition is satisfied in the circuit shown.

The elements should have such values that the following two equations are approximately satisfied 10 in order to balance out the modulation effects:

$$R1(C2+C3) = MuR2C3 \quad (1)$$

$$R1C1(C2+C3) = (R2+R3)C2C3 \quad (2)$$

In these equations:

15 R1=resistance 52

R2=resistance 53

R3=resistance 45

C1=total of capacities 17

C2=total of capacities 15

C3=capacity 46

Mu=amplification factor of tubes 14

Equation (1) above is ordinarily the more important, and does not involve the phase-correcting resistor 46 (R3). For best results, however, 25 this resistor must have the correct value to satisfy Equation (2).

The vacuum tubes used in connection with the circuit comprising the present invention 30 might be of any type, and any means for heating the cathodes of the same may be provided. It is understood, of course, that whereas any 35 of a number of types of tubes are effective and similar in operation, those employing an indirectly heated cathode, such as type 221, are preferred, in which case the heaters are connected to a secondary of the alternating current power transformer which supplies power to the 40 rectifier. These type 221 tubes have an amplification factor of approximately 9. In the push-pull stage, tubes 23 are preferably of type 245.

Although it is understood that a wide variety 45 of circuit constants may be employed in a device operating in accordance with the invention just described, the following constants have been found to be satisfactory:

By-pass condensers 18	.1 microfarad
Resistors 16	1,000 ohms
By-pass condensers 17	.1 microfarad
50 Resistor 18	1000 ohms
Grid condenser 24	.50 microfarads
Grid-leak 25	2 megohms
Plate condenser 26	.002 microfarad
By-pass condenser 27	.1 microfarad
55 Resistor 28	50,000 ohms
Potentiometer 30	.5 megohm
By-pass condenser 31	.5 microfarad
Resistor 32	25,000 ohms
By-pass condenser 34	.1 microfarad
60 Resistor 35	.25 megohm
Resistor 38	.5 megohm
Resistor 39	.1 megohm
Resistor 43	50,000 ohms
Resistor 44	.25 megohm
65 Resistor 45	5,000 ohms
Condenser 46	.5 microfarad
Resistor 50	2000 ohms
Resistor 51	2000 ohms
Resistor 52	5300 ohms
70 Resistor 53	950 ohms
Resistor 54	400 ohms
Choke 55	800 ohms
(Iron-core choke-Speakerfield)	
Choke 56	550 ohms
75 (Iron-core choke)	

The transformer 29 may preferably have a 1:4 ratio. The meter 28 may have a 15 milliamper range.

With the above constants the following voltages will be developed at the stated leads when 5 a difference in potential of 270 volts exists between points 58 and 59:

60	= -130 volts
61	= 80 volts
62	= 51 volts
63	= -37 volts
64	= 30 volts
65	= +80 volts
66	= +140 volts

10

15

The potential of 49 lies between -37 and -30 volts, depending on the position of the contact of resistance 50.

It is obvious, of course, that other constants 20 may be used in the circuit constituting this invention without departing from the scope thereof as set forth in the following claims.

I claim:

1. A fluctuation compensating network comprising a source of direct voltage having undesired fluctuations, two resistances R1 and R2 connected respectively in series from positive to negative terminals of said source, a capacity C1 in parallel with resistance R1, a point connected through a capacity C2 to the junction of said resistors and through a capacity C3 in series with a resistance R3 to said negative terminal, and a vacuum tube having an amplifying factor Mu, a plate connected to said positive terminal, a grid connected to said point, and a cathode connected to said junction, said elements being related substantially in accordance with the following equations:

$$R1(C2+C3) = MuR2C3 \quad 25$$

$$R1C1(C2+C3) = (R2+R3)C2C3 \quad 30$$

40

2. A signaling system comprising an amplifier connected to a three electrode detector coupled to the output of said amplifier having a cathode, 45 anode and control electrode, which detector produces a uni-directional change of voltage dependent on the alternating signal voltage impressed thereon, a volume control tube having a cathode, anode, and control electrode, a connection for coupling the said change of voltage to the control electrode of said volume control tube, means for maintaining the cathode of said volume control tube at a potential greatly negative relative to said amplifier cathode, means for maintaining the anode of said volume control tube at a potential normally slightly negative relative to 50 said amplifier cathode, a resistance in series with the anode of said volume control tube for causing thereon a corresponding change of voltage whereby an increase in the current supplied to said rectifier will produce an increase in the anode-cathode current through said volume control tube, and a connection from the anode of said volume control tube to the control electrode of 55 said amplifier, whereby the amplification of said amplifier is regulated automatically.

3. In a signaling system, a vacuum tube amplifier having a cathode and a control electrode, a vacuum tube detector coupled to the output of 70 said amplifier, said detector having more than two electrodes, including an output electrode, a volume control tube having a cathode, an input and an output electrode, means for maintaining the output electrode of said detector much more 75

positive than the input electrode of said volume control tube, means for maintaining the cathode of said volume control tube greatly negative relative to said amplifier cathode, means for maintaining the output electrode of said volume control tube normally slightly negative relative to said amplifier cathode, means for maintaining the input electrode of said volume control tube slightly more negative than the cathode thereof, 10 means for causing the output electrode of said detector to become more positive in the presence of an amplified signal, means for causing the input electrode of said volume control tube to become proportionally more positive in the presence of an amplified signal, and a direct current connection between the output electrode of said volume control tube and the control electrode of said vacuum tube amplifier, whereby the amplification of said amplifier is regulated automatically. 15

4. In a signaling system, a vacuum tube amplifier having a cathode and a control electrode, a vacuum tube detector coupled to the output of said amplifier, a volume control tube coupled to the output of said detector, said volume control tube having a cathode and an output electrode, means for maintaining the cathode of said volume control tube greatly negative relative to said amplifier cathode, means for maintaining the output electrode of said volume control tube normally slightly negative relative to said amplifier cathode, means for causing said output electrode to become more negative in the presence of an amplified signal, and a direct current connection between said output electrode and said control electrode, whereby the amplification of said amplifier is regulated automatically. 30

5. In a signaling system, a vacuum tube amplifier having a cathode and control electrode, a vacuum tube detector coupled to the output of said amplifier, said detector having at least two electrodes, including an output electrode, a volume control tube having input and output electrodes, means for maintaining the output electrode of said detector substantially more positive than the input electrode of said volume control tube, means for maintaining the input electrode of said volume control tube more negative than the cathode thereof, means for causing the output electrode of said detector to become more positive in the presence of an amplified signal, thereby causing the input electrode of said volume control to become proportionately more positive in the presence of an amplified signal, a direct current connection between the output electrode of said volume control tube and the control electrode of said vacuum tube amplifier, whereby the amplification of said amplifier is regulated automatically, and an alternating current coupling between the control electrode of said amplifier and a point on the source of direct current for said amplifier, whereby voltage fluctuations of said source are coupled to the control electrode of said amplifier to compensate for the fluctuations in amplification occasioned by said fluctuations of said source. 60

6. In a signaling arrangement, a signal responsive system including a vacuum tube having a control electrode, a detector tube coupled to the output of said system, a control tube having an anode, cathode and control electrode, a direct current connection between said anode and the control electrode of said vacuum tube, a unitary source of direct voltage for said tubes, and three

resistors connected in series between the positive and negative terminals of said source, the output of said detector being connected to a point between the first and second of said resistors, and the junction of the second and third resistors being connected to the control electrode of said control tube, whereby the uni-directional component of the rectified current output of said detector, due to signals present in said system, acts upon said control tube to cause it to automatically regulate the responsiveness of said system to said signals. 10

7. A signaling arrangement according to claim 6, in which each of the electrodes of said control tube is maintained, by an individual connection to said unitary source, more negative than the most negative electrode of said detector tube. 15

8. A radio signal receiving apparatus which comprises a carrier current amplifier having a grid electrode, a detector tube having a cathode and an anode, a volume control tube having an input electrode and an output electrode, a resistor connected between said anode and a point of a source of direct voltage, for maintaining said anode more negative than said point, a connection including two resistors in series from said anode to a point of said source, which is more negative than said detector cathode, a connection from said input electrode to the point between said two last-mentioned resistors, a connection including a resistor between said output electrode and a second point of said source for maintaining said output electrode more negative than said second point, a connection between said output electrode and said grid electrode, whereby a decrease in anode current of said detector caused by an increase in the signal voltage causes said anode to become more positive, and said input electrode to become less negative, and said output electrode and hence the grid electrode of said amplifier to become more negative. 30

9. A radio signal receiving apparatus which comprises a carrier current amplifier having a grid electrode, a detector tube having a cathode and an anode, a volume control tube having an input electrode and an output electrode, a resistor connected between said anode and a point of a source of direct voltage, for maintaining said anode more negative than said point, a connection including two resistors in series between said anode and a point of said source which is more negative than said detector cathode, a connection from said input electrode to the point between said two last-mentioned resistors, a connection including a resistor between said output electrode and a second point of said source for maintaining said output electrode more negative than said second point, a connection between said output electrode and said grid electrode, and a connection including a resistor and a condenser in series between said output electrode and a point of said source more negative than said second point, whereby variations in the voltage of said source are compensated by a corresponding variation in the grid voltage of said amplifier. 50

10. A radio signal receiving apparatus which includes a carrier current amplifier having a control electrode and a cathode, a detector tube having a grid, a cathode and an anode arranged for grid rectification, and connected to the output of said amplifier, a resistor connected in the anode circuit of said detector tube, across which is developed a uni-directional rectified voltage which causes the voltage at said anode to become less positive upon an increase of anode current, a 70

volume control tube having a cathode, an input and an output electrode, said input electrode being connected to said anode, whereby variations in the detector anode voltage are impressed on said input electrode, means for causing the cathode of said volume control tube to be more positive than said input electrode, means for maintaining the cathode of said volume control tube greatly negative relative to the cathode of said amplifier, means for maintaining said output electrode normally slightly negative relative to the cathode of said amplifier, a resistor connected between said output electrode and the cathode of said volume control tube, whereby said output electrode becomes more negative when the voltage at said input electrode becomes more positive, and a connection from said output electrode to said control electrode, whereby an increase of the negative voltage of said output electrode decreases the amplification of said amplifier.

11. A radio signal receiving apparatus which comprises a carrier current amplifier having a cathode and a control electrode, a detector tube of the grid-detection type having a plate electrode, a volume control tube having a cathode, an input electrode and an output electrode, a resistor connected in the plate circuit of said detector tube, a connection from said input electrode to said plate electrode, means for maintaining the cathode of said volume control tube greatly negative relative to said amplifier cathode, means for maintaining said output electrode slightly negative relative to said amplifier cathode, a resistor connected between said output electrode and the cathode of said volume control tube, and a connection between said output electrode and said control electrode, whereby an increase in the incoming signal strength creates an increase in the negative bias on the control electrode of said amplifier.

12. In a signaling system, a vacuum tube amplifier having a cathode and a control electrode, a second vacuum tube having an anode connected to an intermediate point on a high resistor, means for coupling the output of said amplifier to said second tube, a third vacuum tube having a grid, a cathode, an output electrode, a connection from said grid to a second intermediate point on said resistor, means for decreasing the anode current in said second tube and thereby positively changing the voltage on said anode in response to an amplified signal, and a direct current connection from the anode of said third tube to said control electrode, whereby the amplification in said amplifier is regulated automatically.

13. A signaling system comprising a vacuum tube amplifier having a cathode and a control electrode, a detector tube, having a cathode and an anode, coupled to said amplifier, a vacuum tube having a cathode, an input electrode and an output electrode, a unitary source of direct voltage for said tubes, three resistors connected in series from the positive to the negative terminals of said source, a connection from the cathode of said detector tube to the junction of the first and second of said resistors, a connection from the junction of the second and third of said resistors to said input electrode, and a direct current connection from said output electrode to said control electrode, whereby the amplification in said amplifier is regulated automatically.

14. In a signaling system, a vacuum tube amplifier having a cathode and a control electrode,

a detector having an anode connected to an intermediate point on a high resistor, means for coupling the output of said amplifier to said detector, a vacuum tube having an input electrode connected to a second intermediate point of said resistor and an output electrode connected to said control electrode, means for maintaining said output electrode normally slightly negative relative to said amplifier cathode, means for changing the anode current in said detector and thereby changing the voltage on said anode in response to an amplified signal, whereby the amplification in said amplifier is regulated automatically.

15. In a modulated carrier signaling system, a vacuum tube amplifier having a direct current source for supplying the space current thereof and a cathode connected to an intermediate point of said source, a high resistor connected across said source, a triode detector coupled to the output of said amplifier, said detector having a cathode connected to said point of said source, and a first anode connected to an intermediate point on said resistor, a vacuum tube having an input electrode connected to a second intermediate point of said resistor which is more negative than said point of said source and an output electrode connected to a control electrode of said amplifier, and means for decreasing the average current of said anode in response to increasing signal output of said amplifier, by an amount substantial as compared with the current in said resistor, whereby the amplification in said amplifier is regulated automatically.

16. In a modulated-carrier signaling system, an amplifier for amplifying the signal, a vacuum tube having a control electrode, means for regulating the amplification in said amplifier in proportion to a change of voltage on said control electrode, another vacuum tube coupled to the output of said amplifier and having an output electrode, a source of direct voltage for supplying space current to said amplifier, a high resistance path connected between two points of substantially different voltage on said source, means for changing the average current of said output electrode in response to increasing signal output of said amplifier, by an amount substantial as compared with the current in said path, and two connections from two intermediate points of substantially different voltage on said path respectively to said control and output electrodes, whereby the resulting voltage change on said output electrode in response to a signal is partially applied to said control electrode for automatically regulating the amplification in said amplifier.

17. In a modulated-carrier signaling system, an amplifier for amplifying the signal, a vacuum tube having a control electrode, means for regulating the amplification in said amplifier in proportion to a change of voltage on said control electrode, another vacuum tube coupled to the output of said amplifier and having an output electrode, a high resistance path having two different intermediate points connected respectively to said control and output electrodes, a common source of direct voltage for supplying space current to said amplifier and for maintaining said electrodes at different voltages, and means for causing a change of voltage on said output electrode in response to a signal, by an amount substantial as compared with the voltage difference between said electrodes, whereby a

- corresponding change of voltage is applied to said control electrode for automatically regulating the amplification in said amplifier.
18. In a modulated-carrier signaling system, 5 an amplifier for amplifying the signal, a vacuum tube having a control electrode, means for regulating the amplification in said amplifier in proportion to a change of voltage on said control electrode, a detector coupled to the output of said 10 amplifier and having an output electrode, a source of direct voltage for supplying space current to said amplifier, a high resistance path connected between two points of substantially different voltage on said source, means for changing the average current of said output electrode 15 in response to increasing signal output of said amplifier, by an amount substantial as compared with the current in said path, and two connections from two intermediate points of substantially different voltage on said path respectively to said control and output electrodes, whereby the resulting voltage change on said output electrode in response to a signal is partially applied
- to said control electrode for automatically regulating the amplification in said amplifier.
19. In a modulated-carrier signaling system, 5 an amplifier for amplifying the signal, a vacuum tube having a control electrode, means for regulating the amplification in said amplifier in proportion to a change of voltage on said control electrode, a detector coupled to the output of said 10 amplifier and having an output electrode, a high resistance path having two different intermediate points connected respectively to said control and output electrodes, a common source of direct voltage for supplying space current to said amplifier and for maintaining said electrodes at different voltages, and means for causing a 15 change of voltage on said output electrode in response to a signal, by an amount substantial as compared with the voltage difference between said electrodes, whereby a corresponding change of voltage is applied to said control electrode for 20 automatically regulating the amplification in said amplifier.

HAROLD A. WHEELER.

CERTIFICATE OF CORRECTION.

Patent No. 2,001,950.

May 21, 1935.

HAROLD A. WHEELER.

It is hereby certified that error appears in the printed specification of the above numbered patent requiring correction as follows: Page 4, second column, lines 45 and 46, claim 2, strike out the words "having a cathode, anode and control electrode," and insert the same after "amplifier" in line 43, of said claim; and page 6, second column, line 23, claim 15, for "a first" read an: and in same line and claim for "an" read a first; and that the said Letters Patent should be read with these corrections therein that the same may conform to the record of the case in the Patent Office.

Signed and sealed this 2nd day of July, A. D. 1935.

Leslie Frazer

Acting Commissioner of Patents.
